[57] CLAIM

The ornamental design for a boat, as shown and described.

DESCRIPTION

FIG. 1 is a top perspective view of a boat showing my new design;

FIG. 2 is a front elevational view thereof;

FIG. 3 is a rear elevational view thereof;

FIG. 4 is a top plan view thereof; and,

FIG. 5 is a right side elevational view thereof, the left side elevational view being a mirror image of that shown.

FIG. 1

FIG. 2

FIG. 3

FIG. 4

FIG. 5
